STORE FIXTURE

Frank M. O'Connor, Austin, Minn.

Application January 6, 1943, Serial No. 471,481

6 Claims. (Cl. 211—49)

This invention relates to supports and racks and more particularly to store fixtures of that kind.

An important object of the invention is to provide a store fixture embodying a plurality of inclined and vertically-adjustable shelves, which are also horizontally adjustable, and carried by a particularly sturdy support.

Another object is to provide a store fixture, including inclined shelves sloping downwardly toward the front, fed from the rear and adapted to carry rows of containers, such as cans, boxes or packages, with the rows separated one from the other, and the containers tending to move forwardly and downwardly by gravity.

Still another object is to provide combined separator and support means, adapted to separate rows of containers on shelves, guide them forward and downwardly, and, in addition, add strength and support to the shelves themselves.

Among the additional objects are to provide sturdy, but light-weight inclined shelves, inexpensive to manufacture, carried by inexpensive end supports, and providing units adapted to be arranged side by side, to make up the shelving of a store or the like.

Other objects will be apparent during the course of the following detailed description, taken in connection with the accompanying drawings, forming a part of this specification and in which drawings:

Figure 1 is an end elevation of the novel store fixture unit.

Figure 2 is a vertical section thereof.

Figure 3 is a front elevation of a plurality of such units.

Figure 4 is a longitudinal section thru an adjustable bracket employed in the novel store fixture.

Figure 5 is a side elevation of the same.

Figure 6 is an enlarged longitudinal section thru portions of a novel inclined shelf and showing the shelf brace and article separator employed.

Figure 7 is a fragmentary section thru the shelf and bracket.

Figure 8 is a pusher, shown partly in elevation and partly in section, which may be employed in combination with the novel fixture.

In the drawings, wherein for the purpose of illustration is shown a preferred embodiment of the invention, the letter A may designate the novel store fixture in general, the letter B the support portion thereof; C the shelves; D end panels carrying the shelves C; E, bracket means

for securing the end panels D to the support portion B; F container separator and guide means; G anchor and support means for the article separator and guide means F and shelves C; and H pusher means for containers of merchandise J.

The novel store fixture A may be made wholly of metal, of metal and wood, mostly of wood, or partly of suitable plastics.

The supports B include, preferably, a pair of substantially V-shaped vertical, spaced-apart members 10, each made up of two lengths of suitable material, suitably secured together at their lower ends 11 and diverging therefrom, with their upper ends 12 joined by a cross plate 13. The lower ends 11 are secured to a base piece 14 and may be braced as at 15 while the pair of members 10 may be joined together in any suitable manner as by cross member 16, whereby the V-shaped members are held in upright positions, as is apparent. With this construction, a pair of opposed inclined or sloping faces or surfaces 17 are provided for each member 10, as shown in Figures 1 and 2.

The shelves C are of novel construction and each comprises, preferably, a single elongated sheet 20 of suitable material, preferably flexible or bendable, provided with means at its forward end 21 to form a stop for merchandise. This means may comprise a turned-up portion 22 of the shelf material, as shown in Figures 1 and 2. The rearward end 23 of the shelf is higher than the forward end 21, since the shelf slopes upwardly from, preferably, near the forward end. There may be provided a substantially flat portion 24 to the shelf extending rearwardly from the forward end 21 so that merchandise carried at this forward end will be substantially vertical. Preferably each shelf is of the same depth.

Extending from adjacent the forward end 21 of each shelf, toward the rearward end 23 are a plurality of spaced apart slots or openings 25. These openings 25 may begin just slightly rearwardly of the flat portion 24, and are for a purpose later described.

Two spaced apart end panels D are provided to carry each shelf C. Each panel D, shown particularly in Figure 6, may comprise an upright section 30 having a suitably sloping upper edge 31 with this edge 31 sloping rearwardly and upwardly from the front. It is upon the sloping edges 31 of each pair of panels that the shelf rests, and may be suitably secured thereto. Thus, if the shelf C comprises a bendable metallic sheet, the latter will assume the contour of the

edges 31 when the shelf is upon the end panels. In any case, the material making up the shelf is so fashioned that it will assume this contour.

The end panels D also include suitable means to detachably secure them to the bracket means E. This means may comprise an enlargement 32 at the base of each upright section 30, extending from, preferably, the front of the upright section, toward the rear, but considerably short of the upright section 30, as shown in Figure 6. Each enlargement 32 may have paralleling opposite side faces 33 with a slot 34 extending thru the enlargement from face to face 33, for a purpose to be described.

The bracket means E preferably comprise telescoping members 35 and 36, the member 36 telescoping within the hollow member 35. Each member 35 is provided with beveled end faces 37 and 38 and a row of spaced-apart screw-threaded sockets 39 in one side face 40. A screw-threaded perforation 41 is also provided in its lower face 42 adjacent the end face 38. The telescoping member 36 may have only one beveled end face 43, this being its outer end face. A set screw 44 is provided for the perforation 41 and adapted to bear against the lower face 45 of the telescoping member 36 when the latter is within or partly within the member 35.

These bracket means E are adapted to extend horizontally from one sloping face 17 to the opposite sloping face 17 of the supports B, with the beveled end faces 37 and 38 or 37 and 43, as the case may be, in intimate contact with the faces 17. Thus the bracket means are wedged into place. It is apparent that vertical adjustment of the bracket means E, along each V-shaped member 10 is possible, by lengthening or shortening the bracket means and setting it in its correct position by means of the set screw 44. Generally, two or three different lengths of bracket means E are required in order to position the various bracket means, one above the other, in suitable spaced-apart relation, but generally, only one length of end panel D is required and one depth of shelf C.

So that all shelves C will have their forward ends 21 in substantially the same vertical plane, the end panels D may be secured to the bracket means E in a horizontally adjustable relation by means of suitable bolts 46 which extend from one side face 33 (the inner side face) thru the slot 34, thru the opposite side face 33 of the enlargement 32 and into the screw-threaded sockets 39 of the telescoping member 35, the bolts, of course, having screw threads at one of their ends to cooperate with the screwthreads in the walls of the sockets 39. Thus the panels D have an adjustable horizontally sliding relation with the bracket means E.

It is obvious that the shelves C may be quickly raised or lowered simply by loosening the set screws 44 and extending or retracting the telescoping members 36, and again tightening the set screws when adjustment is made.

A novel article separator and guide means F is provided. This comprises suitable lengths 50 of material, preferably wire, provided with hooks 51 and 52 at the ends of each, and adapted to extend across and above the shelves from front to rear with the hook 51 engaging the forward end 21 and the hook 52 engaging the rearward end 23, substantially as shown in Figure 6 with the wire taut. Each length 50 is disposed over and paralleling a slot 25. These lengths 50, suitably spaced apart, provide guideways for containers of

merchandise J adapted to slide down the shelves C, by gravity, but they also provide in cooperation with the anchor and support means G, braces for the shelves.

5 These anchor and support means G comprise short lengths of suitable material, as lengths 55 of wire, having a small eye 56 at one end of each, embracing a length 50 of wire but slideable therealong. The anchor wire lengths 55 depend from 10 the guide wire lengths 50 and extend thru the slots 25 where their lower ends 56 are provided with screw threads to cooperate with a nut 57, or like means, which may bear against the under side of the shelves C in such a relation that the lengths 15 55 are made taut and, of course, maintain the guide wire lengths 50 taut as well. This also provides substantial bracing for the shelves, since from six to twelve or more guide wires may be employed with each shelf C.

20 A suitable pusher means H for containers of merchandise J may be employed for urging the containers J downwardly and forwardly, the means H being positioned to the rear of the rear-most container of each row of containers. This 25 means H may comprise a housing 60, open at its bottom and to which is rotatably connected a roller 61 extending partly within and partly under the housing 60. Either end 62 of the housing 60 may contact the rearward face of the 30 most rearward container J and thus tend to urge all containers, in the same row, forwardly.

The shelves C are preferably supplied, with rows of containers J, from the rear end, and as the most forward containers are removed, the 35 row will move forwardly over the surface of the shelf, urged by gravity and, if desirable, by the pusher means H.

Heights of containers J govern the positions 40 of the bracket means E and the number of container separator and guide means F employed with each shelf, is, of course, governed by the width of the containers J.

While the shelves are relatively light-weight, 45 they are rendered strong and the bracket means E cooperating with the support portion B, provides a sturdy but easily adjusted assembly. Two or more of the fixtures A may be placed side by side, as shown in Figure 3, and the shelves C adjusted to accommodate containers of various 50 heights.

Various changes may be made to the shape, size and arrangement of parts, without departing from the spirit of the invention or the scope of the following claims.

55 I claim:

1. In a display and self-serving rack, a pair of spaced-apart V-shaped supports, end means for holding said supports in upright positions, shelf brackets carried by said supports and having beveled ends, adapted to engage, in intimate contact, the sloping surfaces of said supports, an end panel mounted upon each bracket, and a shelf carried by a pair of said end panels.

60 2. In a display and self-serving rack, a pair of spaced-apart V-shaped end supports, end means for holding said supports in upright positions, telescoping brackets carried by said supports and having beveled ends, means retaining 65 said brackets in various vertically adjusted positions with said beveled ends in intimate contact with the sloping surfaces of said supports, a shelf, a pair of spaced-apart end panels, with said panels sloping upwardly from the front of said 70 rack, said shelf being mounted upon said panels 75

and sloping therewith, and means detachably securing said end panels to said brackets.

3. In a display and self-serving rack, a pair of spaced-apart, substantially V-shaped end supports, end means for holding said supports in upright position, a shelf, a pair of vertically-extending end panels having their upper edges sloping upwardly and rearwardly from the front portion of said rack, with said shelf mounted upon said edges and substantially following the contour of their sloping upper edges, and means securing said panels to said supports, including brackets having bevelled end faces in contact with said supports in wedging relation therewith.

4. In a display and self-service store fixture, spaced-apart vertical end supports, a sloping shelf mounted upon said supports and having an upwardly-extending forward edge and a rearward edge above said forward edge, a guide wire extending tautly from said forward edge to said rearward edge and above said shelf, an anchor wire slidably secured to said guide wire and depending therefrom, and means for retaining said anchor wire taut between said guide wire and shelf.

5. In a display and self-service store fixture, spaced-apart vertical end supports; an elongated shelf extending between said supports, having a forward edge and a rearward edge and a slot extending transversely thru said shelf intermediate said edges; end panels having their upper edges sloping rearwardly and upwardly from the front of said rack, with said shelf mounted upon

said upper edges and substantially following the contour of said upper edges; means securing said end panels to said end supports; a guide wire extending tautly above said shelf from said forward to said rearward edges and paralleling said slot; an anchor wire, slidably secured to said guide wire and extending thru said slot; and means below said shelf and bearing upwardly upon the under side thereof, for retaining said anchor wire taut.

6. In a merchandise display unit adapted to cause merchandise to move forward by gravity, spaced-apart vertical supports; an elongated shelf of relatively thin flexible material, supported upon said supports, and provided with a forward edge, a merchandise stop at said forward edge, a rearward edge disposed above said forward edge, and a slot extending transversely thru said shelf intermediate said edges; end panels having upwardly and rearwardly sloping upper edges; means securing said end panels to said supports; a guide wire extending above said shelf from said forward edge to said rearward edge and over said slot; a taut anchor wire, secured at one end to said guide wire and extending downwardly thru and below said slot with the other end of said anchor wire provided with screw threads, and a nut with its screw threads cooperating with said first named screw threads and bearing against the under side of said shelf, whereby said anchor wire will retain said guide wire taut and brace said shelf.

FRANK M. O'CONNOR.
